UNITED STATES PATENT OFFICE.

JEAN VÖLKER, OF NEU ISENBURG, GERMANY, ASSIGNOR TO THE FIRM OF PETER WEIL & CO., OF RODELHEIM, NEAR FRANKFORT-ON-THE-MAIN, GERMANY.

RIBBON-FEED MECHANISM FOR TYPE-WRITERS.

No. 884,691.

Specification of Letters Patent.

Patented April 14, 1908.

Application filed February 12, 1906. Serial No. 300,675.

To all whom it may concern:

Be it known that I, JEAN VÖLKER, manufacturer, a subject of the German Emperor, and resident of Neu Isenburg, near Frankfort-on-the-Main, Germany, have invented certain new and useful Improvements Relating to Ribbon-Feed Mechanism for Type-Writers, of which the following is a specification.

10 This invention relates to ribbon-feed mechanism for type writing machines by which the rotary movement of the spring-barrel indirectly imparts motion to the ribbon during each forward step of the carriage. The improved mechanism differs from previous mechanisms of this kind in so far that it translates the rotary motion of the spring barrel into oscillatory motion for two push-rods provided with double clawkers adapted 20 to impart motion to the ratchet-wheels keyed on the shafts of the ribbon-spoils.

In order to render the invention clear, I will describe the same with reference to the accompanying drawings, in which:

25 Figure 1 is a plan of the improved intermediate mechanism for transmitting the motion. Fig. 2 is a side-view of the ratchet of one of the ribbon-spoils showing the clawkers disengaged. Fig. 3 is a similar view of 30 the ratchet with the clawkers in engagement. Fig. 4 is a front view of the reversing bar and showing the push-rods in section. Fig. 5 is a perspective view of the complete mechanism. Fig. 6 shows the spring barrel and connected parts in operative positions during 35 the forward movement of the carriage. Fig. 7 shows the same parts in their inoperative positions during the return travel of the carriage.

40 According to my invention I provide the rear side of the spring barrel *m* of the machine with teeth *n* rising at their inner sides towards the barrel shaft as is clearly shown in Fig. 5, the teeth being of a generally inverted 45 ed V formation with rounded ridge. A lever *s* fast on a shaft *t* is arranged to reach with its free end as far as the tooth *n* and has a short bend *v* by which it carries a pawl *o* whose motion is limited towards the rear 50 by a stop *p* resting against the edge of the end *v*. The free end of the pawl *o* is furnished with an anti-friction roller *q*. The pawl *o* swivels on a pin on whose lower end is mounted a spring *r* so constituted as to press

the stop *p* against the end *v* of the lever *s*. 55 On the shaft *t* is fixed a short arm held by a tension spring *u* which is attached to a rigid part of the machine and tends to press the lever *s* and its pawl *o* with roller *q* into the teeth *n* of the spring-barrel. 60

Presuming the spring barrel *m* to turn during the advance of the carriage in the direction of the arrow shown in Fig. 6, and that then the free end of the lever *s* with its pawl *o* is in the dotted position, the roller *q* 65 resting in the hollow between the teeth, when the barrel turns, as stated, until the ridge of a tooth operates against the roller *q* and lifts the pawl *o*, the stop *p* of the pawl *o* will be pressed against the corner of the 70 bend *v* of the lever *s* and the latter will thus be moved outwards to the position shown in full lines at Fig. 6. At the continued motion of the barrel *m* the roller *q* slides down the 75 rear of the tooth by reason of the action of spring *u*. It will thus be obvious that the lever *s* receives oscillatory motion from the revolving barrel.

At the return travel of the carriage, the spring barrel turns in the direction of the 80 arrow shown in Fig. 7 and the pawl *o* will at first enter the hollow of the tooth as indicated by dotted lines in Figs. 6 and 7. The further rotation of the barrel then causes the next tooth to press the pawl *o* rearward 85 against the pull of its spring *r* but without lifting the lever *s*, this being due to the stop *p* moving free on the lever in the opposite direction into the position shown in full lines at Fig. 7. In this case the pawl works idle 90 and produces no oscillatory motion of the lever *s*.

The lever *s* is situated at the side of the machine and has a lateral angular arm *s*¹ which is pivoted by a pin *c* to a push rod *k*. 95 The rod *k* carries at its front end a plate *g* formed with central slot adapted to take round the vertical spindle *d* of the ribbon spool, which spindle is fitted with a ratchet wheel *b* as shown. The plate *g* has four lugs 100 *e* to form bearings for pivoted clawkers *f* and *f*² which are arranged to operate in opposite directions. As there is a ribbon spool at each end of the machine for the successive winding of the ribbon from one on to the other, it will be necessary to employ a similar ratchet mechanism for such spool. 105 For this purpose I provide a fixed lever arm

z at the other end of the shaft t. The lever arm z is connected by a pin c¹ to a horizontal push-rod k¹ to whose free end is fixed a slotted plate g¹ with lugs e¹ forming bearings for clawkers f¹ and f³. These are alternately made to operate the ratchet wheel h¹ on the spindle d¹ that engages in the slot of the plate g¹. When the latter is moved forward by the action of the lever s, the clawker 10 f¹ engages in a tooth of the ratchet h¹ and so turns the same in the direction of the arrow shown in Figs. 1 and 3, while the clawker at the other side of the ratchet passes over the tooth thereof and then drops into the next 15 tooth and prevents the wheel turning backward. At the retreating movement of the plate g¹ the clawker f¹ becomes operative and turns the wheel h¹ still further in the same direction, while the clawker f³ moves idly 20 over a tooth and then drops behind the same to stop the wheel in that direction.

The clawkers f, f², f¹ and f³ keep in engagement with the ratchet teeth by their own weight providing the positions of the push rods k and k¹ allow of it. By lifting the one or the other of said rods, the clawkers will be held on rests y, y¹ and y², y³ respectively without touching the ratchets. In this manner and so long as the plate g¹ is in its lowered 30 position, the ratchet wheel h¹ will be continuously turned in a uniform direction until the ribbon is fully wound on the spool on the shaft. The end of the ink ribbon may be differently colored or be fastened to a 35 piece of different ribbon so as to indicate when the ribbon is unwound. When this occurs it will be necessary to reverse the movement, that is to say, the spindle d¹ and ratchet wheel h¹ must be set free while the 40 ratchet h has to be driven. For this purpose it will be required to lift the rod g¹ of the ratchet h¹ and at the same time lower the rod k with its plate g on the ratchet wheel h. This is effected by means of a horizontal rail 45 or bar a which is appropriately guided on the machine, say by means of slots a¹ and pins a². The bar a is placed edgewise and has at its upper edge two shallow recesses b and b¹ at such a distance apart as to cause one of 50 the push-rods, such as k¹, to be in the recess b¹, while the other push-rod k is away from its recess a and rests on the top edge of the bar a as shown in full lines, or reversed as indicated by dotted lines in Fig. 4. Thus, 55 the rod k¹ is in this position slightly lower than the rod k and the clawkers f¹, f³ of the former are in engagement with the ratchet wheel, while the clawkers f and f² are disengaged. The bar a can be shifted endwise 60 from one position to another by means of a small handle x at the front of the machine giving motion to such bar a through a rod i and crank arm w with slot and pin connection as shown. Thus the position of the 65 handle x indicates the direction of travel of

the ribbon and need only be turned sidewise at the proper moment in order to reverse the movements.

Having now fully described my said invention, what I claim and desire to secure by Letters Patent is:

1. In a typewriter the combination with the spring barrel of inverted V-shaped teeth formed with a broad base and a rounded ridge and arranged on the back side of the 75 barrel, of a spring controlled lever keyed upon a shaft pivotally secured to the machine frame work, the said lever coöperating with the teeth of the spring barrel with the intermediary of an antifriction roller, means 80 for preventing the lever from being operated when the spring barrel rotates backward and means for converting the oscillatory motion of the said lever into a rotary motion and transmitting the latter to the ribbon spool 85 spindles substantially as and for the purpose described.

2. In a typewriter the combination with the spring barrel of teeth arranged on the back side of the latter, of a spring controlled 90 lever keyed upon an oscillating shaft, of a bent part arranged on the upper end of the lever, a spring controlled pawl pivotally connected to the said bent part, an antifriction roller, carried on one end of the pawl and co-operating with the teeth of the said spring barrel, a stop on the opposite end of the said pawl which normally rests against the said bent part and is adapted to cause the said lever to oscillate during the forward travel 100 only of the barrel, means for transmitting the oscillating motion of the said lever to the ribbon spool spindles in the form of a rotary motion, substantially as and for the purpose described.

3. In a typewriter the combination with a spring barrel of teeth arranged on the rear side of the latter, of a spring controlled lever oscillated by the said teeth, an oscillating shaft carrying the said lever, arms secured one to the said lever and the other to the said shaft on the opposite side of the machine, horizontal push rods articulated to the said arms and carrying at their free ends slotted plates engaging the vertical ribbon spool 110 spindles, oppositely arranged clawkers co-operating with horizontal ratchet-wheels keyed upon the ribbon spool spindles, means for alternately throwing one of the said pushing rods in and out of gear, substantially as 115 and for the purpose set forth.

4. In a typewriter the combination with a spring barrel of teeth arranged on the rear side of the latter, of a spring controlled lever oscillated by the said teeth, an oscillating shaft carrying the said lever, arms secured one to the said lever and the other to the said shaft on the opposite side of the machine, horizontal push rods articulated to the said arms and carrying at their free ends slotted 125 130

- plates engaging the vertical ribbon spool spindles, clawkers oppositely arranged on the said plates and adapted to rotate at each motion of the push rods, horizontal ratchet 5 wheels keyed upon the ribbon spool spindles, rests for the clawkers when inoperative, and means for raising or lowering alternately one of the said push-rods, substantially as and for the purpose set forth.
- 10 5. In a typewriter the combination with a spring barrel of teeth arranged on the rear side of the latter, of a spring controlled lever oscillated by the said teeth, an oscillating shaft carrying the said lever, arms secured 15 one to the said lever and the other to the said shaft on the opposite side of the machine, horizontal push rods articulated to the said arms and carrying at their free ends slotted plates engaging the vertical ribbon spool 20 spindles, clawkers oppositely arranged on the said plates and adapted to rotate at each motion of the push rods, horizontal ratchet wheels keyed upon the ribbon spool spindles, rests for the clawkers when inoperative, a 25 hand operated slide bar guided on the machine transversely to the said push-rods and adapted to support the latter on its upper edge, shallow recesses arranged in the said upper edge of the bar and so distributed as to 30 cause one of the push rods to be in its recess while the other push rod rests on the plain edge of the bar, substantially as and for the purpose described.
6. In a typewriting machine the combination 35 of a spring barrel provided with teeth and adapted to rotate in reverse directions, ribbon spool spindles provided with ratchet teeth, rods provided with pawls adapted to engage said teeth, means for throwing one of 40 said rods and its pawls out of operative relation with its spindle, said means throwing the remaining rod and its pawl into operative relation with its spindle, levers connected with said rods, and a spring actuated dog
- connected with one of said levers and adapted 45 to have rigid and yielding engagement therewith whereby rotation of said barrel in one direction will serve to operate said lever through said rigid connection, said yielding connection permitting said dog to operate 50 idly.
7. In a typewriting machine the combination of a spring barrel provided with teeth and adapted to be rotated in reverse directions, ribbon spool spindles provided with 55 ratchet teeth, rods provided with pawls adapted to engage said teeth, levers connected with said rods, and a spring actuated dog connected with one of said levers and adapted to have rigid and yielding engagement therewith when coöperating with said spring barrel whereby rotation of said barrel in one direction will serve to operate said levers through said rigid connection, said yielding connection permitting said dog to 60 operate idly when said barrel is rotated in an opposite direction.
8. In a typewriting machine the combination of a spring barrel provided with teeth and adapted to be rotated in reverse directions, ribbon spool spindles, means for rotating said spindles, and a spring actuated dog associated with said means and adapted for engagement with the teeth of said barrel, said dog having a rigid and yielding engagement 70 with said means whereby rotation of said barrel in one direction will serve to operate said means through said dog and rigid connection, said yielding connection permitting said dog to operate idly during rotation of 75 said barrel in an opposite direction.

In testimony, I have hereunto set my hand in presence of two witnesses.
